UNITED STATES PATENT OFFICE.

HENRY BAUER, OF INDIANAPOLIS, INDIANA.

EXTENSION-TABLE.

SPECIFICATION forming part of Letters Patent No. 415,376, dated November 19, 1889.

Application filed November 29, 1887. Serial No. 256,380. (No model.)

To all whom it may concern:

Be it known that I, HENRY BAUER, a citizen of the United States, residing at Indianapolis, in the county of Marion and State of Indiana, have invented certain new and useful Improvements in Extension-Tables, of which the following is a specification.

In the manufacture of extension-tables it has heretofore been the usual custom to secure the slides to the table-top by means of a rectangular block glued to the side of said slide and the under side of the top of the table. While this construction has been cheap and simple, it has been the means of many disastrous accidents, in that while tables so constructed were heavily loaded with dishes the glue would oftentimes give way and precipitate the load onto the floor and break the dishes, thus causing considerable loss and trouble. In some cases, too, the slides have been made of metal and provided with laterally-projecting ears, through which screws have been inserted into the table-top as the means for securing them in place; but this construction is also insecure.

The object of my said invention is therefore to provide a simple and cheap device for securely holding the table-top and the slides together, and thus, while not adding any expense to the construction of the table, overcome the above-mentioned disadvantage, as will be hereinafter more fully set forth.

Referring to the accompanying drawings, which are made a part hereof, and on which similar letters of reference indicate similar parts, Figure 1 is a perspective view showing the character of table to which my invention relates; Fig. 2, an under side plan of the same, showing the slides secured in position by means of my said invention; Fig. 3, a detail sectional view through the parts to which my invention is immediately related, on the dotted lines 3 3 in Figs. 2 and 4; Fig. 4, a view looking upward from the dotted lines 4 4 in Fig. 3; and Fig. 5, a view similar to Fig. 3, but showing the old construction.

In said drawings, the portions marked A represent the table; B, the slides thereof; and C, C', and C², the parts of my improved device for securing the slides and table together.

The table A and slides B are not in them-

selves dissimilar from the ordinary construction, and need no special description herein.

The device for securing the slides and table together consists of a plate C with a central perforation, in which is mounted an ordinary bolt C', provided upon its end with a nut C², two of which are preferably employed at each end of a slide. The plate C is of a thickness equal to the width of the space it is desired to have between the top of the slide and the under side of the table-top, it being necessary to have a slight space between the two to prevent chafing and rubbing. It is secured to the underside of the table by means of screws or analogous devices at the position where it is desired to secure the slide, a recess a being formed in the under side of said table to receive the head of the bolt, which projects above the top of said plate. The slide, being provided with suitable perforations, is then put in position on the bolts C', and the nuts C² are screwed on, thus securing the slide rigidly to the table in the position desired, a washer c being preferably provided between each of said nuts and the wood, and said nuts and washers being preferably sunk into the slide, so as to be hid from sight. The top part of the slide bears against the underside of the plate and the heads of the screws which secure said plate in position, as will be readily seen, and thus prevent said screws from working out. The plate maintains the desired space between the two parts, and prevents them from chafing against each other as the table is extended or closed, and said parts are at all times rigidly secured together beyond all danger of falling apart. By this construction I not only overcome the before-mentioned disadvantage of the old construction, but also secure to the table a new advantage, in that the slides can be quickly and easily removed from the table and slides of different lengths substituted at pleasure, thus permitting dealers to furnish a customer with a table of the exact length desired without keeping in stock a large number of complete tables of different lengths, as has heretofore been necessary.

In order that the old construction in common use may be easily understood, I have shown it in Fig. 5, which is a view similar in

character to Fig. 3, wherein is shown a block D, glued to the table and slide for securing the parts together, and a block d, glued between the parts to secure the desired space between them.

I am aware that it is not new to fasten a bolt to a part by inserting it through a perforated plate and securing said plate to said part with the head of the bolt under the plate; but I do not regard this as anticipating my invention, as herein claimed, by which great and peculiar advantages are secured to the particular device shown, as above described.

Having thus fully described my said invention, what I claim as new, and desire to secure by Letters Patent, is—

1. The combination of the table A, slide B, the bolt C', provided on its head end with the plate C, said plate C secured to the under side 20 of the table and formed of a thickness to se-

cure the desired space between the table-top and slide, and said bolt extending through said slide, whereby said parts are rigidly secured together, substantially as set forth.

2. The combination, with the top A, slide 25 B, the bolt C', inserted through a perforation in a plate C and extending down through said slide, said plate C being secured to the top of the table, with the bolt-head above its top face, and being formed of a thickness equal to the 30 desired space between said slide and said table-top, substantially as described, and for the purposes specified.

In witness whereof I have hereunto set my hand and seal, at Indianapolis, Indiana, this 35 21st day of November, A.D. 1887.

HENRY BAUER. [L. S.]
